UNITED STATES PATENT OFFICE.

LOUIS FABER AND PHILIP SCHNEIDER, OF CHICAGO, ILLINOIS, ASSIGNEES TO FABER-SCHNEIDER RADIATOR COMPANY, OF CHICAGO, ILLINOIS, A CORPORATION OF ILLINOIS.

RADIATOR.

Application filed May 16, 1921. Serial No. 469,774.

To all whom it may concern:

Be it known that we, LOUIS FABER and PHILIP SCHNEIDER, citizens of the United States, residing at Chicago, in the county of Cook and State of Illinois, have jointly invented certain new and useful Improvements in Radiators, of which the following is a specification.

This invention relates to a new and improved radiator, and more particularly to a radiator of the type particularly adapted for use in connection with the cooling systems of internal combustion engines.

In such radiators it is now customary to provide a plurality of tortuous passages so formed as to present a large area for contact with the air. The efficiency of the radiator is limited by the area of exposed cooling surface and is further limited by the facility with which air may reach and pass over such cooling surfaces.

In certain types of radiator the flattened water passages are formed with a number of twists or turns and adjacent passages are brought into contact to form a cellular structure. Such forms of radiators are objectionable in that the points where the adjacent cooling passages contact are obviously not exposed to the cooling influence of the air.

In other forms the cooling passages have been separated by a plurality of separator members so that the passages may be reached by air from all sides. These forms are inefficient in that they require a relatively large area of radiator construction in order to afford adequate cooling area. In radiators, especially those adapted for use upon motor vehicles, compactness is an essential feature.

It is an object of the present invention to provide a radiator construction having a plurality of adjacent water passages, these passages connected into a unitary structure by separating means, the separating means, however, affording air passages adjacent all parts of the surface of the water cooling members.

It is an additional object to provide a device of this character in which two separate air spaces are provided between each

adjacent pair of water cooling members, one such space adjacent each member, the members thus being kept out of contact with each other, and the spaces forming continuous air passages both longitudinally and transversely.

It is also an object to provide a structure in which this is accomplished by means of a single spacing element placed between each pair of adjacent water cooling elements.

It is a further object to provide a device of the character described which is compact and affords a maximum of radiation surface and which is composed of but few and relatively simple parts and which may be manufactured at small cost.

Other and further objects will appear as the description proceeds.

Broadly, our invention comprises a series of juxtaposed water cooling members with a separator plate interposed between each pair of such members. Portions of the plate are laterally displaced in opposite directions, and these displaced portions are attached to the two adjacent water cooling members. The major portion of the separator plate is, however, unattached to either such water cooling member, and preferably air passages extending both longitudinally and laterally of the surfaces of the water cooling members are provided between each such member and its adjacent separator plates.

We have illustrated a preferred embodiment of our invention in the accompanying drawing, in which—

Figure 1 is a general view of the radiator structure according to our invention;

Figure 2 is a fragmentary view on an enlarged scale showing a portion of the construction;

Figure 3 is a vertical transverse section taken on line 3—3 of Fig. 5;

Figure 4 illustrates a series of elements used in forming the radiator; and

Figure 5 is a section taken on line 5—5 of Figure 2.

As shown in the drawings, the radiator is formed of a plurality of corrugated plates 6, these plates having their edges laterally

offset from the main body of the plate. Between each pair of such plates 6 is located a separator plate 8 having its edges 9 offset in a manner generally similar to that of the plates 6. The offsets on the plate 6 as shown are of such a type that when the plates are juxtaposed hexagonal cells are formed.

As shown in Figure 3, when the edges of the several plates are brought together there is formed between the adjacent plates 6 a channel W adapted to receive water. This channel has portions of alternately greater and less cross section due to the peculiar configuration of the forming plates.

15 The spacing plates 8, as best shown in Figure 3, have their central or body portion entirely flat, their edges only being deformed or laterally displaced so as to be engaged by and attached to the adjacent water 20 passage forming plates. The offset of the edges of the plate 6 is such that, as best shown in Figure 3, these plates, although joined at the edges to the plates 8, are elsewhere separated from such plates forming 25 air passages A which are also of varying cross section as are the water passages. These air passages extend longitudinally of the radiator plates—that is, vertically as shown in Figure 3. Transverse air passages 30 13 through the radiator are also formed between the plates.

The radiator may be preferably manufactured by placing against each other a plurality of sections as shown in Figure 4, in 35 which a water passage forming plate 6 is placed upon each side of a spacing plate 8. The laterally displaced edge portions 10 of the plate 8 are alternately brought into contact with the adjacent portions of each of 40 the two water passage forming plates 6.

It will be observed that these portions 10 have a depressed portion 11 formed adjacent thereto. These depressions 11 are short and extend a relatively small portion of the 45 width of the plate, serving to receive the ends of the depressed portions 12 of the water passage forming plates, these latter depressions being best shown in Figure 3. The depressions 12, however, extend substantially the full width of the plates 6, their ends being pocketed in the depressions 11 upon opposite edges of the plate 8. The depressions 12 increase the area of the 50 water passage and also by their seating in the depressions 11 aid in maintaining the plates 6 and 8 in their proper relation both laterally and longitudinally when handling the plates in forming the radiators.

It will be observed that each element, as 60 shown in Figure 4, is provided with two vertically extending air passages separated by the plate 8. It is also provided with transversely extending apertures 13. When two such elements are placed together, the 65 water passage W is formed between them,

this passage thus being flanked upon each side by an air passage and being nowhere in contact with an adjacent water passage. Moreover, no air passage is in contact with the walls of two water passages, but with 70 one alone.

In forming the radiator a plurality of elements as shown in Figure 4, of proper length, is placed in a form or jig and the edges of the plates are dipped in molten 75 solder in order to fully close the ends and maintain the plates in proper relation. The completed radiator element then is placed in the radiator body 14 or has its upper and lower faces connected in any desired manner to radiator body members to form a water tight connection therewith.

Obviously the effective thickness of the water passages may be varied by varying the amount of the offsets upon the edge of 85 the plates. However, these offsets are limited by the nature of the material and the facility with which it flows under forming pressure.

The plates 6 and 8 may be readily formed 90 by passing strips of the proper width through forming rolls and may be easily bent and placed into proper relation, as shown in the drawing.

The structure is very simple in design 95 and inexpensive to manufacture, and is very efficient in supplying both vertically and transversely extending columns of air to the water cooling passages throughout the exposed surface of the passages.

We claim:

1. A radiator structure comprising a series of juxtaposed water carrying members, and a single separator plate interposed between each adjacent pair of such members, 105 the edges of the separator plates being formed with portions displaced laterally from the longitudinally extending imperforate body of the plate, said displaced portions extending alternately in opposite directions and being attached alternately to the two juxtaposed water carrying members and the body of the plate being spaced from both said members in such manner as to form continuous air passages both longitudinally and transversely of the members between each said member and the spacer plate.

2. A radiator structure comprising a series of paired plates, the edges of said plates being inwardly displaced and joined in such manner that a closed water carrying member is formed therebetween, the pairs of plates each being provided with reverse transverse bends, adjacent pairs being so placed as to be substantially parallel, and a spacing plate between each pair, the edges of the plate being laterally displaced to alternately engage the two adjacent paired plates, the central body portion of the spac- 130

ing plate being spaced from both said adjacent plate pairs in such manner as to form a longitudinally extending air space between the spacing plate and each water carrying member, the bends of all said plate edges being similar in design and size and affording flat contacting surfaces whereby the several plates are joined in such relation as to form a structure having a uniform hexagonal cellular face. Signed at Chicago, Illinois, this 9th day of May, 1921.

LOUIS FABER.
PHILIP SCHNEIDER.
